METHOD TO IMPROVE THE WATER-SOLUBILITY OF INSOLUBLE OR INSUFFICIENTLY SOLUBLE ORGANIC MATERIALS

Richard Hueter, Dessau-Röslau, Anhalt, and Heinz-Joachim Engelbrecht, Dessau, Anhalt, Germany, assignors, by mesne assignments, to "Unichem" Chemikalien Handels A.-G., Zurich, Switzerland, a corporation of Switzerland

No Drawing. Application June 19, 1937, Serial No. 149,094. In Germany June 20, 1936

12 Claims. (Cl. 167—31)

It is known that those organic materials which are insoluble or insufficiently soluble in water, such as remedies, disinfecting agents, vermin-combating means etc., e. g. phenols, phenol-homologues and their substitution-products, etheric oils, menthol, camphor, organic bases such as nicotine, pyridine, quinoline and the like, are rendered soluble in water, if they are combined with soaps. As suitable for the purpose are to be considered *inter alia*: the soaps obtained from olein, castor oil or from more unsaturated fats, as well as soap-like substances such as Turkey-red oil.

The experiences had with the use of such soap-bearing preparations have proved, that the proportion of soap is not at all unrelated to the efficiency of the total preparation. We must know that the soap-addition, in applying comparatively small amounts, causes apparently an enhancement of the efficiency, whilst higher soap-additions cause, as a rule, a considerable diminution of the degree of efficiency.

The present invention is based on the fact, hitherto unknown, that such variations in the efficiency of the processes are to a large extent dependent upon the molecular weight of the fatty acid on which the soap or, respectively, the soap-like acting substances are based. Thus it could indeed be stated, that e. g. the disinfecting efficiency of a phenol-mixture, which by a determined soap-addition in the form of olein-potash soap is practically annulled, suffers nearly no diminution, if instead of the olein-potash soap one employs the same amount of a soap obtained from low molecular fatty acids (compare Example 1).

The soaps obtained from fatty acids with no more than 12 C atoms have proved particularly well adapted for the purposes in question and preferably from fatty acids containing from 6—10 C atoms. In following this method we are not exclusively confined to the fatty acid salts, but we may also employ suitable condensation-products of the fatty acids with organic residues containing water-solubilizing groups. Thus we may apply e. g. the fatty acid esters and fatty acid amides containing in the ester- or amide-group respectively a water-soluble residue and particularly a sulfuric acid- or sulfonic acid-residue. We may use also fatty acid esters of polyvalent alcohols, wherein a hydroxyl-group of the polyvalent alcohol-residue is esterified with sulfuric acid or substituted by the SO₃H-group. In these cases too the disinfecting power of the preparations diminishes in the same proportion

as the chain-length of the alkyl-residue or, respectively, the molecular weight of the fatty acid is increased. The aforesaid condensation-products of the fatty acids show in the same manner the property of converting water-insoluble substances into aqueous solutions.

The described behaviour of the soaps and soap-like derivatives of low molecular fatty acids with no more than 12 C atoms in the molecule makes it possible to apply these products in the manufacture of aqueous solutions serving as pharmaceutical, bacteria-destroying, fungicidal etc. media, and particularly of aqueous disinfecting means or, respectively, of preparations to destroy any noxious or disease-exciting micro-organisms. In employing soaps of higher fatty acids it is generally impossible to limit the addition of the soap or of the soap-like product to just the best-proportioned amount with regard to the disinfecting efficiency, as this addition as a rule will not suffice to secure the transparency with any dilutions or the permanent clearness and stability of those dilutions during a long standing and storage, whereas in employing the low fatty acids the addition may be increased to a large extent without fearing any appreciable reduction of the disinfecting power. Moreover, certain combinations of disinfecting agents with higher molecular soap-products e. g. soap-products based on oleic acid, which contain no sufficient amount of such means to secure the permanent clearness and furthermore any soap or, respectively, condensation-products of low fatty acids, may be admixed to such an extent, that the combination will not be disintegrated even in any desired dilution. It is therefore advisable to jointly employ such fatty acid soaps or soap-like fatty acid derivatives which contain higher fatty acid radicals. However, these components should be present only in such an amount that they would not alone be sufficient to render the total product dilutable with any quantity of water.

Example 1

Six and two-tenths parts by weight of a phenol-mixture consisting of 1.8 parts of p-chlorine-m-cresol, 1.8 parts of chloroxylenol, 1.0 parts of chlorothymol and 1.6 parts of chlorocarvacrol are supplied in 93.8 parts of an aqueous solution containing such an amount of caprylic acid potash-soap as to give to the total product a proportion of 13.5% of caprylic acid.

This mother-solution diluted at the ratio of 1:100 and 1:200 with water, caused after a re-

acting-time of half a minute with both dilutions the perfect extermination of *Staphylococcus* and *coli-bacillus*. In replacing in the aforesaid preparation the caprylic acid potash-soap by equal amounts of olein-potash-soap, the same dilutions could with an even 5 minutes' reaction not attain the complete extermination. And even after reducing the olein-soap-addition to 5% of oleic acid (calculated on the mother-solution) the dilutions of 1:100 and 1:200, after half a minute to one minute were not able to destroy entirely the *Staphylococcus* and the *coli-bacillus*.

Similar results were obtained if instead of the caprylic acid soap one employs the alkali salts of the undecyl acid, caproic, capric or caprylic acid or mixtures of same respectively.

Example 2

Two and five-tenths parts by weight of p-chlorine-m-cresol, 1.0 parts of chloroxylenol and 2.7 parts of chlorocarvacrol are dissolved together with 30.7 parts of the sodium salt of the sulfuric acid ester of glyceryl ester of caproic acid in 10 parts of spirit and 53.1 parts of distilled water.

This mother-solution, after a dilution with water at the proportion of 1:200 causes within half a minute the complete extermination of *Staphylococcus* and *coli-bacteria*.

When the aforesaid sulfuric acid ester was replaced by the same amount of mono-palmitoyl-glycerin sodium combined with sulfuric acid, the complete extermination could under the same conditions not be obtained.

Instead of the mono-caproyl-glycerin sodium combined with sulfuric acid we may likewise apply the caprylic acid ester of the isethionic acid sodium as well as similarly constituted soap-products.

Example 3

A phenol-mixture consisting of 1.8 parts by weight of p-chlorine-m-cresol, 1.8 parts of chloroxylenol, 1.0 parts of chlorothymol and 1.6 parts of chlorocarvacrol is supplied in 93.8 parts of an aqueous soap-solution, the soap-proportion of which, calculated on fat, is 12% and for the manufacture of which one applied as the fatty acid base the commercial caprylic acid and olein in the ratio of 2:1. The solution, after dilution with water in the ratio of 1:200 is sufficiently potent to cause, after one minute, the complete extermination of *Staphylococcus* and *coli-bacteria*.

Under the same conditions, when soap produced only with olein is used there occurs no destruction. In the same manner as with olein soap, similar results could be obtained with other fatty acid soaps such as ricinoleic alkali etc. in combination with soaps obtained from low fatty acids.

We claim:

1. An aqueous solution consisting of materials of the group consisting of phenols and fatty acid derivatives containing fatty acid radicals of 6 to 10 carbon atoms of the group consisting of soaps, soap-like fatty acid esters containing in the ester group a water solubilizing radical, and soap-like fatty acid amides containing in the amide group a water solubilizing radical.

2. An aqueous solution consisting of materials of the group consisting of phenols and fatty acid derivatives of the group consisting of fatty acid soaps and fatty acid soap-like derivatives containing fatty acid radicals of 6-10 carbon atoms

together with fatty acid derivatives of the group consisting of fatty acid soaps and fatty acid soap-like derivatives containing fatty acid radicals with more than 12 carbon atoms wherein the quantity of the higher molecular fatty acid derivative is less than one part out of three parts by weight of the total fatty acid content of said solution.

3. An aqueous solution consisting of materials of the group consisting of phenols, phenol-homologues, substitution products of the phenol-homologues and fatty acid soaps containing fatty acid radicals with 6 to 10 carbon atoms.

4. An aqueous solution containing materials of the group consisting of phenols, phenol-homologues, substitution products of the phenol-homologues and fatty acid soaps containing fatty acid radicals with 6 to 10 carbon atoms together with fatty acid soaps containing fatty acid radicals with more than 12 carbon atoms wherein the proportion by weight of the fatty acid soaps containing 6 to 10 carbon atoms in the molecule to the soaps containing more than 12 carbon atoms in the molecule is at least 2 to 1.

5. An aqueous solution comprising materials of the group consisting of phenols, phenol-homologues, substitution products of the phenol-homologues and as a water solubilizing agent fatty acid derivatives of the group consisting of soaps, salts of the sulfuric acid esters of the mono-fatty-acid-esters of polyvalent alcohols, salts of the fatty acid esters containing a sulfonic acid group and salts of the fatty acid amides containing a sulfonic acid group, said fatty acid derivatives being composed of compounds having 6 to 10 carbon atoms in the fatty acid radical and compounds having more than 12 carbon atoms in the fatty acid radical, wherein the proportion by weight of the fatty acid derivatives containing 6 to 10 carbon atoms in the fatty acid radical to the fatty acid derivative containing more than 12 carbon atoms in the fatty acid radical is at last 2 to 1.

6. An aqueous solution consisting of a phenol mixture consisting of p-chloro-m-cresol, chloroxylenol, chlorothymol, chlorocarvacrol and the sodium salt of the caprylic acid.

7. An aqueous solution consisting of a phenol mixture consisting of p-chloro-m-cresol, chloroxylenol, chlorocarvacrol and the sodium salt of the mono-caproyl-glycerine-sulfuric acid-ester.

8. An aqueous solution consisting of a phenol mixture and a mixture of sodium salts of caprylic acid and of oleic acid wherein the ratio by weight of the sodium salt of caprylic acid and the sodium salt of oleic acid is at least 2 to 1.

9. An aqueous solution containing phenols and a dissolving agent wherein the dissolving agent consists of material of the group consisting of soaps of fatty acids having 6 to 12 carbon atoms in the molecule, sulfates and sulfonates of mono-fatty acid esters of glycerin wherein the fatty acid radical contains 6 to 10 carbon atoms in the molecule.

10. An aqueous solution containing phenols and a dissolving agent wherein the dissolving agent consists of material of the group consisting of soaps of fatty acids and sulfates and sulfonates of mono fatty acid esters of glycerin wherein at least two-thirds by weight of the dissolving agent contains fatty acid radicals having 6 to 10 carbon atoms in the molecule.

11. The process of producing stable solutions of phenols in water without impairing the germi-

cidal or antiseptic properties of the phenols which comprises forming the solution of phenols in water in the presence of a water solubilizing agent selected from the group of fatty acid derivatives consisting of soaps, soap-like fatty acid esters containing in the ester group a water solubilizing radical and soap-like fatty acid amides containing in the amide group a water solubilizing radical said fatty acid derivatives

containing at least two parts out of every three parts by weight of fatty acid derivatives having 6 to 10 carbon atoms in the fatty acid radical.

12. A stable clear aqueous solution of a phenol containing as a dissolving agent a sodium salt of the isethionic ester of caprylic acid.

RICHARD HUETER.
